(57) CLAIM

The ornamental design for a door panel, as shown and described.

DESCRIPTION

FIG. 1 is a perspective view of a first embodiment of a door panel design according to this invention;

FIG. 2 is a front view of the door panel design of FIG. 1;

FIG. 3 is a cross-sectional view of the door panel design of FIG. 1 taken along line 3—3 in FIG. 2;

FIG. 4 is a cross-sectional view of the door panel design of FIG. 1 taken along line 4—4 in FIG. 2;

FIG. 5 is a front view of the door panel design of FIG. 1, the panel design being incorporated into a face of a section of a metal sectional overhead door shown in broken lines;

FIG. 6 is a perspective view of a second embodiment of a door panel design according to this invention;

FIG. 7 is a front view of the door panel design of FIG. 6;

FIG. 8 is a cross-sectional view of the door panel design of FIG. 6 taken along line 8—8 in FIG. 7;

FIG. 9 is a cross-sectional view of the door panel design of FIG. 6 taken along line 9—9 in FIG. 7; and,

FIG. 10 is a front view of the door panel design of FIG. 6, the panel design being incorporated into a face of a section of a metal sectional overhead door shown in broken lines.

The views of the door panel not shown form no part of the claimed design. The broken lines depicting doors, door panels, and other ornamental and functional elements of such doors represent environmental elements only and form no part of the claimed design. The height-to-width ratios of the panel design may vary from the ratios of the specific embodiments shown in the Figures without departing from the claimed design.
